(57) **CLAIM**

The ornamental design for a combined washer and dryer as shown and described.

DESCRIPTION

1. Combined washer and dryer
- 1.1: Front perspective view
- 1.2: Rear perspective view
- 1.3: Front
- 1.4: Back
- 1.5: Left
- 1.6: Right
- 1.7: Top
- 1.8: Bottom
- 1.9: Exploded

The broken lines shown in the reproductions depict portions of the combined washer and dryer and form no part of the claimed design; reproduction 1.9 shows a state of the front cover being detached from the main body.
